UNITED STATES PATENT OFFICE.

STANLEY WESTCOTT HOLMES, OF SAN DIEGO, CALIFORNIA.

HOLDER OR PRESS FOR TENNIS RACKETS AND SIMILAR ARTICLES.

Application filed April 9, 1921. Serial No. 460,054.

To all whom it may concern:

Be it known that I, STANLEY W. HOLMES, a citizen of the United States, residing at San Diego, in the county of San Diego and 5 State of California, have invented certain new and useful Improvements in a Holder or Press for Tennis Rackets and Similar Articles; and I do hereby declare the following to be a full, clear, and exact description of the invention, such as will enable others skilled in the art to which it appertains to make and use the same.

The present invention relates to clamps or presses for holding the frames of rackets 15 (such as are used in playing lawn or court tennis, or similar implements) rigid and in shape when not in use, as when stored away or being transported, so as to prevent warping of the frames under the tension of the 20 strings, dampness, or the like.

It is the object of the invention to provide a clamp of that kind which is exceedingly simple and compact, which will be disposed snugly against the opposite sides of the 25 frame or head of the racket, within the outline thereof, and which will enable the racket with the clamp thereon to be inserted within the usual cover or glove without hindrance, and which will also serve its 30 purpose of holding the frame rigidly in shape.

The racket clamps usually used are rather clumsy, inasmuch as they occupy more or less space at the opposite sides of the frame 35 and beyond the margin of the frame, so that such clamps must be used on the exterior of the cover or glove, making it rather awkward to carry or pack, whereas a racket with the present clamp applied can be readily 40 packed, and several of them conveniently placed within a suit case or trunk, without the possibility of injury to other contents.

A further object is the provision of such a clamp having clamping plates of novel 45 form to bear against the opposite sides of the racket frame, and novel means for drawing said plates toward one another, whereby to clamp the frame, and providing a simple, light and compact device which is convenient and efficient in use.

With the foregoing and other objects in view, which will be apparent as the description proceeds, the invention resides in the construction and arrangement of parts hereinafter described and claimed, it being understood that changes can be made within

the scope of what is claimed, without departing from the spirit of the invention.

The invention is illustrated in the accompanying drawing, wherein:—

Figure 1 is a plan view of the clamp as applied to the frame of a tennis racket, the handle being broken away.

Fig. 2 is a cross section on the line 2—2 of Fig. 1.

The clamp comprises a pair of opposite side plates for clamping the frame F of the racket between them, and the plates are preferably constructed of suitable wood, or other rigid and preferably light material. 70 The plate comprises the parallel transverse bars 4 at its opposite ends, the longitudinal parallel connecting bars 5 having their ends united with the bars 4 at points spaced from the ends of said bars 4, and a cross piece 75 or bar 6 disposed transversely between the bars 4 and united with the bars 5. These bars or pieces 4, 5 and 6 are flat and in the same plane, and the bars 4 are cut away, as at 7, at those sides which are disposed 80 against the frame, and at the ends of said bars which overlap the frame, as shown, whereby the side plates are partially received within the tennis racket frame, as seen in Fig. 2. The ends of the bars 4 are 85 also cut obliquely and bevelled off, as at 8, so as to terminate within the outline of the racket frame, and prevent said ends from cutting into other objects and enabling the racket and clamp to be readily inserted into 90 the cover or glove.

In order to secure the clamping plates together on the frame of the racket, a tubular threaded nut or socket 9 is anchored within each bar 4 of one plate, between the 95 ends of said bar, said socket or nut having a flange 10 embedded in the bar 4, as shown in Fig. 2. These sockets or nuts 9 project from the corresponding clamping plate, and can be readily inserted between the strings 100 S without the possibility of injuring such strings. Screws 11 are carried by the other plate, and said screws are swivelled through pieces 12 of metal secured, by means of screws 13, or the like, to the bars 4 of the 105 corresponding plate between the ends of said bars, so that said screws register with the nuts 9 when the plates are placed on the racket in proper position. The screws 11 have heads 14 of minimum height bearing 110 on the pieces 12, and the screws are retained in place by means of pins 15 engaging

through said screws under the pieces 12. Finger pieces 16, of bail shape as shown, are pivotally connected with the heads 14 whereby they can be swung to a position at 5 an angle with the clamp, for conveniently rotating the screws, and can be swung against the corresponding plate, as shown, so as to occupy very little space on the side of the clamp. The bars 4 which have the 10 screws 11 are provided with recesses 17 for receiving the nuts 9 when the clamping plates move together sufficiently.

In using the clamp, the side plate which has the nuts 9 is first placed against the 15 side of the racket, and the nuts 9 inserted between the strings. The other plate is then placed against the opposite side of the frame, and the screws 11 will readily enter the nuts 9, without contacting with the 20 strings. Then, by rotating the screws to screw them into the nuts 9, the opposite clamping plates are drawn together at their opposite ends and the frame of the racket will be clamped tightly at four points between the ends of the bars 4, thereby rigidly 25 holding the frame, and preventing warping thereof. The clamp is so compact that it

can be inserted with the racket in the usual cover or case and has other advantages as hereinbefore pointed out.

Having thus described the invention, what is claimed as new is:—

A racket press comprising opposite clamping plates having transverse end bars and longitudinal bars connecting them, the 35 end bars having their terminals projecting and adapted to fit against and overlap the opposite sides of the racket frame, and means for connecting said plates intermediate the ends of said end bars, each of said 40 means including a nut secured to one plate and projecting therefrom to pass between the strings of the racket and a screw swivelled for rotation in the other plate to enter the nut and draw the plates toward one 45 another.

In testimony whereof I have signed my name to this specification in the presence of two subscribing witnesses.

STANLEY WESTCOTT HOLMES.
